UNITED STATES PATENT OFFICE

PERCIVAL P. BERRY, OF WEST ROXBURY, MASSACHUSETTS, ASSIGNOR TO ENGLANDER SPRING BED COMPANY, OF BROOKLYN, NEW YORK, A CORPORATION OF NEW YORK

BED

Application filed August 13, 1924. Serial No. 731,736.

This invention relates to couch beds, and more particularly to that class designated as sliding couch beds or day beds, an object of the invention being to provide an improved sliding couch bed in which the sections have spiral mattress supporting springs housed one under the other, and in which means is provided for automatically raising and lowering one set of spiral springs on the sliding 5 of one of the sections of the bed.

10 A further object of the invention is the provision of an improved sliding couch bed having means operative to slide one of the sections relatively to the other and to also 15 raise or lower the spring mattress or springs of one of the sections.

15 A further object of the invention is the provision of an improved sliding couch bed, in which means is provided for not only 20 sliding one of the sections relatively to the other and for raising or lowering the spring mattress or springs thereof, but also for folding and unfolding the stuffed mattress carried by the springs.

25 An important feature of the present invention resides in the provision of means for automatically raising and lowering the spring mattress or spiral springs of one section 30 to the other, and which means in the embodiment shown is also effective to slide one of the sections relatively to the other and to fold and unfold a stuffed mattress, and which means in the present instance consists of an 35 operating member shown in the form of a swinging bar so connected to the bed sections that the entire operation of shifting the sliding section, raising and lowering the spiral spring carrying frame and folding and unfolding the mattress is obtained by the 40 simple operation of this bar, the construction being such that the entire operation of opening and closing the bed is not only accomplished by this single bar with but little 45 effort or strength but an improved bed is provided which may be operated easily and efficiently, is relatively inexpensive to manufacture, easy to handle and move around, readily knocked down, and in appearance 50 will form an attractive article of furniture.

Other objects of this invention will appear in the following description and appended claims, reference being had to the accompanying drawings forming a part of this specification, wherein like reference characters indicate corresponding parts in the several views and wherein Fig. 1 is a perspective view of the bed structure; Fig. 2 is an end view showing the bed sections in closed position, with the stuffed mattress and head 55 and foot members omitted; Fig. 3 is an end view showing the bed sections in open position, the stuffed mattress and head and foot in like manner being omitted; Fig. 4 is a detail perspective end view illustrating particularly the operating mechanism for the sliding section; Fig. 5 is an end view showing the sliding section in extended or open position prior to elevating the mattress section; Fig. 6 is a detail view showing the manner 60 in which the end members are detachably connected to the main section; Fig. 7 is a fragmentary plan view of the bed structure 65 in open position, the stuffed mattress being omitted; Fig. 8 is a fragmentary view illustrating parts of the supporting frame and sliding mattress frame for the sliding section; and Fig. 9 is a detail view showing the 70 operating mechanism for the sliding bed section.

75 Before explaining in detail the present improvement and mode of operation thereof, I desire to have it understood that the invention is not limited to the details of construction and arrangement of parts which are illustrated in the accompanying drawings, 80 since the invention is capable of other embodiments, and that the phraseology which I employ is for the purpose of description 85 and not of limitation.

90 The present improved couch bed, a preferred embodiment of which is illustrated in the drawings, comprises in general a pair of relatively slidable bed sections, and in the present instance the bed is constructed 95 in the form of a normally stationary main section having upright end members, or head and foot members, detachably connected to the main section, and a sliding section shiftable into and out of position within the main 100

section. The sliding bed section in general comprises a sliding frame, and supported thereby is a spring mattress or spiral spring supporting frame shiftable or slidable vertically within the bed section frame. The main section is provided with spiral springs or a spring mattress, and mechanism is provided for shifting the sliding bed section from a position beneath the springs of the main section to extended or open position, and also for vertically raising the spiral springs so as to bring the tops of the two sets of springs into substantially horizontal alignment. In the present instance the entire operation of shifting the sliding section, and raising and lowering the springs of one section thereof, is accomplished by the simple movement of swinging an operating bar.

In its present preferred form the main bed section comprises a pair of end frames, each end frame comprising a transverse angle bar 9 bent downwardly at its ends to provide depending legs 10 and 11, which are connected together by a transverse bar 12. The end frames at opposite ends of the main section are suitably connected together by means of longitudinally extending bars 13. Extending crosswise of the side bars 13 are a series of metal straps or bars 15 upon which are supported the spiral or compression springs 14 for the mattress, these being wired together in any suitable manner and connected by means of tension springs to the transverse bars 9 of the main section.

The sliding bed section comprises a pair of end frames 16, one at each end of the section, and each end frame is in the present instance rectangular in form and including a lower transverse bar 16^a bent upwardly at its end to provide vertical bars 16^b and 16^c which are secured together by a top transverse bar 16^d. Each vertical bar 16^c is extended above the horizontal top bar 16^d a suitable distance at 17, and a stop member 18 is secured to the upper end of the extended portion 17. This stop member 18 is adapted to engage the said bar 13 of the main section and limit the outward movement of the sliding section. The end frames 16 are connected together at opposite sides by lengthwise extending side bars 19, and the frame of the sliding section is mounted upon suitable rollers 20 to permit the same to be readily shifted into and out of housed position beneath the spring mattress 14 of the main section. The sliding bed section is provided with spiral springs 21 which are mounted upon a frame shiftable vertically within the frame 16 of the sliding section. This spiral spring carrying frame comprises a pair of transverse end bars 22, one at each end of the sliding section, connected together by lengthwise extending side bars 23 and 24. Each end bar 22 of the sliding section is provided with a part 25 extending beyond the bar 24, and this extension 25 is provided with

a notched portion 26 at the end thereof which cooperates with the vertical edge of the angle bar 16^c of the main frame of the sliding section, (see Fig. 7). At its opposite end each bar 22 is notched at 27 (see Fig. 8) to cooperate with a vertical edge of the angle bar 16^b of the main frame 16 of the sliding section. In this way the spiral spring carrying frame is guided in a vertical path against displacement relatively to the frame 16. A series of transverse straps or bars 28 extend crosswise between the side bars 23 and 24 of the vertically movable frame, and supported by these are a series of spiral or compression springs 29 suitably wired together at 30.

Secured to the top and near the inner end of each transverse bar 9 of the main section is a bracket 31 and pivoted to these brackets at opposite ends of the main section is a U-shaped operating bar 32 which extends the length of the main section, and the ends of which are pivoted to the brackets 31 at opposite ends of the main section. This construction permits the close coupling of a pair of detachable heads to the main section of the bed in the manner hereinafter described. By means of a series of operating members or links and levers at each end of the bed the entire operation of the sliding bed section with its sliding mattress section is controlled through the swinging movement of the U-shaped bar 32. Since each series or set of operating members at each end of the bed is identical one set only will be described herein. Pivoted at 33 to the bar 32 is a link 34 which is pivoted at its opposite end 35 to a lever 36. This lever is pivoted or fulcrumed intermediate its ends at 37 to the extended part 17 of the bar 16^c of the frame 16. Adjacent its opposite end the lever 36 is also pivoted at 38 to an operating link 39, the operation of which controls the raising and lowering of the spring mattress of the sliding bed section. Secured to the inner side of the lower transverse bar 16^a of the frame 16 is a strap 40 (see Figs. 3 and 4). An angle lever 42 is pivoted at its lower end 41 to the outer end of the strap 40, and a similar lever 44 is pivoted at its lower end 43 to the inner end of the strap 40. These levers 42 and 44 are adapted to be swung from an approximately horizontal position shown in Fig. 2 to an approximately vertical position as shown in Fig. 3. Each lever in the present instance is angularly bent in the same direction, and a link 47 is pivoted at 45 to lever 42 and at 46 to the lever 44, thus connecting the levers together for simultaneous operation. The operating link 39 is pivoted at 48 to the lever 44. The lever 42 at its upper end is provided with a projecting pin 49 which travels within a lengthwise extending slot 50 formed in the vertical side and at one end of the bar 22 of the sliding mattress frame. In like manner the lever 44 at its upper end is provided with a pin 51 adapted

to travel in a similar slot 52 formed adjacent the opposite end of the horizontal bar 22.

5 A tension spring 53 is connected at one end 54 to the bar 16^a of frame 16, and at its opposite end is connected at 55 to the lower part of lever 42.

10 Each bar 10 and 11 of the end frames of the main section are provided with a pair of vertically spaced slots 56 and 57. An upright end frame, head or foot member 58 is detachably connected to each end of the main bed section, in the present instance each end member comprising a tubular bar 59 which is bent at its ends to provide depending legs 60. 15 Secured adjacent the lower end of each leg 60 is a plate 61 provided with a pair of projecting hooks 62 and 63, the hooked ends of these hooks extending upwardly and are adapted to be inserted into the slots 56 and 57 20 whereby the main section is detachably supported upon the end frames 59. An upwardly projecting headed pin 64 is secured to each end bar 22 at one side of the side bar 24 and at each end of the sliding section, the purpose 25 of this pin being to assist in guiding the mattress section vertically and by engagement with the side bar 13 assist in positioning and locking the mattress and sliding sections against rearward movement or play.

30 The present improved bed is provided with a foldable stuffed mattress, comprising a section 65 located upon the spring mattress of the main bed section, and a section 66 secured to the edge of the stuffed mattress section 65 35 and adapted to be folded upon the section 65 when the bed is closed and to be swung over upon the spiral springs of the sliding bed section when the bed is open. The stuffed mattress section 66 has a part 67 thereof embracing the U-shaped bar 32, so that by swinging this bar the foldable section 66 of the 40 stuffed mattress will be folded and unfolded.

45 In the present bed structure it will be noted that the U-shaped operating bar 32 at its ends is pivoted to the brackets 31 on top of the transverse bars 9 of the main bed section, so that the swinging operation of this bar will not interfere with the upright end members 59. It will also be observed that the lever 36 50 at the upper end thereof extends outside the transverse bar 9, and is bent inwardly at 36^a so as to operate between the vertical member 11 of the main section and the vertical member 16^c of the sliding section. The plates 61 55 secured to the legs 60 of the end members 59 act as spacer members for spacing the bars 10 and 11 of the end frames from the end members 59 sufficiently to permit the operation of the lever 36.

60 When the present improved structure is used as a daybed the sliding bed section is housed within the framework of the main section, and the spring section 21 with its spiral springs 29 is in its lowered position 65 housed within the framework of the sliding

bed section, and this framework in the closed position of the bed shown in Fig. 2 is located beneath the springs 14 of the main section. At the same time the stuffed mattress section 66 is folded upon the section 65. The bed is opened by grasping the U-shaped bar 32 and swinging it from the position shown in Fig. 2, where it extends over the main section, upwardly and over upon the sliding section to the position shown in Fig. 3. 70 Since the U-shaped bar 32 is connected to the framework 16 of the sliding section through the medium of link 34 and lever 36 pivoted at 37 to the bar 16^c, the initial swinging movement of the U-bar 32 will operate to shift the sliding section horizontally from beneath the main section. The forward pull on link 34 will not at this time swing member 36 about pivot 37 to raise the mattress section 21, since the power necessary to shift the sliding section is less than the leverage required to elevate section 21. In other words, as shown the construction and location of the links and levers are such that the initial movement of the swinging 75 operating lever 32 first exerts its power through link 39 to shift the sliding section, since less power is required to do this, owing to the fact that the sliding section rolls easily than is required to raise or lower the 80 mattress. When the U-bar 32 reaches its vertical position, as shown in Figs. 1 and 5 the sliding bed section will reach its full extended position, and the stop members 18 will engage the side bar 13 of the main section, thereby limiting any further outward movement of the sliding section. At the same time the foldable section 66 of the stuffed mattress will be in 85 vertical position as shown in Fig. 1. Upon 90 swinging the U-bar 32 from its vertical position downwardly upon the sliding section the shiftable spring mattress 21 of the sliding section will be raised into the position shown in Fig. 3. This operation is accomplished by means of operating link 39 connected to lever 36, and levers 42 and 44 connected together by means of link 47, these 95 levers operating through pins 49 and 51 in horizontal slots 50 and 52 of the shiftable 100 mattress frame. Thus it will be seen that when the bed is in the position shown in Fig. 5, or Fig. 1, upon the further swinging of the U-bar 32 downwardly toward the 105 sliding section, the lower end of lever 36 110 will be swung inwardly upon the fulcrum 37 as shown in dotted lines in Fig. 5 thereby pulling on the link 39 and swinging levers 42 and 44 from approximately horizontal 115 position (see Fig. 5), to approximately vertical position, (see Fig. 3). This movement of the levers is transmitted to the spiral 120 spring carrying frame or section 21 of the sliding bed section thus elevating the same. 125

130 By swinging the U-bar 32 in the opposite

direction the spring carrying frame or section 21 will first be lowered and then the entire sliding bed section will be shifted into position beneath the springs of the main bed section. It is important to note that a single swinging operation of the U-bar 32 from the position in Fig. 2 to the position in Fig. 3 accomplishes the entire operation of horizontally shifting the entire sliding bed section and raising or lowering the sliding spring section 21. Furthermore this same operation folds and unfolds the mattress 66.

It will be particularly noted that the weight of the stuffed mattress section 66 when folded downwardly from a vertical position shown in Fig. 1 upon the sliding bed section will assist materially in lifting the spring section 21, so that the latter half of the swinging movement of the U-bar 32 is accomplished without any substantial effort since the weight of the stuffed mattress section 66 assists in this movement. The elevation of the spring section 21 is further assisted by means of springs 53, one at each end of the sliding section. These springs are under tension when the spring section 21 is housed within the frame of the sliding bed section, as shown in Figs. 1 and 5. When the U-bar is swung down to raise the spring section 21 the action of the springs 53 assist in raising the levers 42. When the levers 42 are fully raised as shown in Fig. 3 they will be automatically locked in position and will effectually support the sliding spring section 21, which cannot be lowered except by swinging the U-bar 32.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

50 1. In a sliding couch bed, the combination of a pair of relatively slidable couch bed sections each including mattress supporting spiral springs, the spiral springs of one section being housed under and parallel with those of the other section, and means operative to slide one of the sections and to automatically raise and lower the spiral springs of one of the sections.

60 2. In a sliding couch bed, the combination of a pair of relatively slidable couch bed sections each including mattress supporting spiral springs, the spiral springs of one section being housed under and parallel with those of the other section, a folding mattress, and means operative to slide one of the sections

and automatically to raise and lower the spiral springs of one of the sections, and to fold and unfold said mattress.

3. In a sliding couch bed, the combination of a pair of relatively slidable couch bed sections each including mattress supporting spiral springs, the spiral springs of one section being housed under and parallel with those of the other section, and means including means shiftable over the tops of said bed sections for sliding one of the sections into closed or extended position and for automatically raising or lowering the spiral springs thereof, whereby they will be substantially level with and in juxtaposition to those of its companion section or in position to be housed thereunder. 70

4. In a sliding couch bed, the combination of a pair of relatively slidable couch bed sections each including mattress supporting spiral springs, the spiral springs of one section being housed under and parallel with those of the other section, a folding mattress, and means including means shiftable over the tops of said bed sections for sliding one of the sections into closed or extended position and for automatically raising or lowering the spiral springs thereof, whereby they will be either substantially level with and in juxtaposition to those of its companion section or in position to be housed thereunder and to also fold and unfold said mattress. 80

5. In a sliding couch bed, the combination of a pair of relatively slidable couch bed sections having a horizontal position in all positions of said sections, each carrying mattress supporting spiral springs, those of one section shiftable under those of the other section, a vertically shiftable frame carrying the spiral springs of one section, a foldable mattress, and means for sliding one section and also for automatically raising and lowering said shiftable frame and its spiral springs and folding and unfolding said mattress, the spiral springs of the two sections being in juxtaposition when the vertically shiftable frame is raised thereby to form a continuous mattress supporting surface. 100

6. In a sliding couch bed, the combination of a pair of relatively slidable couch bed sections each comprising a supporting frame and each carrying mattress supporting spiral springs, those of one section shiftable under those of the other section, a vertically shiftable frame carrying the spiral springs of one section, and means for sliding one section and also for automatically raising and lowering said shiftable frame and its spiral springs and comprising an operating bar connected to said supporting frames and vertically shiftable frame. 115

7. In a sliding couch bed, the combination of a pair of relatively slidable couch bed sections having a horizontal position in all positions of the sections, each carrying mattress 120

130

- supporting spiral springs, those of one section slidable under those of the other section, a vertically shiftable frame carrying the spiral springs of one section, a foldable mattress, and means for sliding one section and 5 also for automatically raising and lowering said shiftable frame and its spiral springs and comprising an operating bar connected to said sections and vertically shiftable frame and connected to the folding mattress for also folding and unfolding said mattress. 10
8. In a sliding couch bed, the combination of a main mattress carrying section and a sliding section slidable under the top of the main section, a vertically shiftable mattress carrying frame carried by said sliding section, and means for sliding the sliding section and when in its fully extended position for also raising and lowering the vertically shiftable frame and comprising a swinging bar connected with the main section and link-connected with the sliding section and the vertically shiftable frame. 15
9. In a sliding couch bed, the combination of a main mattress carrying section and a sliding section slidable under the top of the main section, a vertically shiftable mattress carrying frame carried by said sliding section, means for sliding the sliding section and when in its fully extended position for also raising and lowering the vertically shiftable frame and comprising a swinging bar connected with the main section and link-connected with the sliding section and the vertically shiftable frame, and a folding mattress also connected to said swinging bar and folded and unfolded by the swinging of said bar. 20
10. In a sliding couch bed, the combination of a main section frame carrying mattress supporting spiral springs, a sliding section frame, a vertically shiftable frame carried by the sliding section and also carrying mattress supporting spiral springs and shiftable with said sliding section under the spiral springs of the main section, said spiral springs having a horizontal position in all positions of said frames, and a swinging bar pivotally connected to the top of the main section frame and link connected to the sliding section frame and to the shiftable frame thereof and operative to slide the sliding section and also to raise and lower the vertically shiftable frame thereof. 25
- 55 11. In a sliding couch bed, the combination of a main section carrying mattress supporting spiral springs, a sliding section, a vertically shiftable frame carried by the sliding section and also carrying mattress supporting spiral springs and shiftable with said sliding section under the spiral springs of the main section, a swinging bar pivotally connected to the top of the main section and link connected to the sliding section and to the shiftable frame thereof and operative to slide 30
- the sliding section and also to raise and lower the vertically shiftable frame thereof, and a foldable mattress carried by said sections and connected with said swinging bar and folded and unfolded on the sliding of said section and the raising or lowering of the vertical frame thereof. 70
12. In a sliding couch bed, the combination of a mattress carrying bed section, a sliding section, a vertically shiftable mattress carrying frame carried by said sliding section, and means operative to slide the sliding section into an extended position and then thereafter to also raise the vertically shiftable frame thereof and to lower said frame and then thereafter to slide the sliding section under the top of the main section. 75
13. In a sliding couch bed, the combination of a mattress carrying bed section, a sliding section, a vertically shiftable mattress carrying frame carried by said sliding section, means operative to slide the sliding section into an extended position and then thereafter to also raise the vertically shiftable frame thereof and to lower said frame and then thereafter to slide the sliding section under the top of the main section, and a foldable mattress also connected with said operating means and folded and unfolded thereby. 80
14. In a sliding couch bed, the combination of a pair of relatively shiftable couch bed sections, each having a spring mattress housed one under the other, said sliding section having a raisable and lowerable spring mattress thereby to bring the same into position substantially level with the spring mattress of its companion section or to lower it into position to be housed under the spring mattress of its companion section, a folding stuffed mattress carried by said sections, and swinging means connected with the two bed sections and the shiftable spring mattress and operative during the first part of its swinging movement to slide one of said bed sections and to partially unfold the stuffed mattress and then during its final swinging movement to raise the spring mattress of one section and completely unfold the stuffed mattress. 90
15. In a bed structure, the combination of a main section having a spring mattress, a sliding section having a spring mattress and means for shifting the sliding section in a horizontal plane and raising or lowering the spring mattress thereof thereby to bring the two mattress sections into substantially level position when the sections are extended, and a foldable mattress also opened and closed by the operation of said shifting means. 115

Signed at Hyde Park, Mass., this 7th day of August, 1924.

PERCIVAL P. BEBRY.
